COLLAPSIBLE THREE-MIRROR VANITY CASE

Freeman Snider and Margaret B. Snider,
Santa Barbara, Calif.

Application April 22, 1957, Serial No. 45,824

Term of patent 14 years

(Cl. D86—10)

FIG. 1.

FIG. 2.

FIG. 3.

FIG. 4.

FIG. 5.

FIG. 6.

FIG. 7.

FIG. 8.

Fig. 1 is a perspective view of a collapsible three-mirror vanity case, showing our new design in open operative position with the storage chest in open position also;

Fig. 2 is a front elevational view of Fig. 1 with the storage chest in closed position;

Fig. 3 is a left side elevational view of the device in completely closed position;

Fig. 4 is a right side elevational view of the device in partly open position, before extension of the mirrors;

Fig. 5 is a view of aspect similar to Fig. 4, but showing the device after extension of the mirrors;

Fig. 6 is a top plan view of Fig. 2;

Fig. 7 is a rear elevational view of the device in completely closed position; and

Fig. 8 is a top plan view of Fig. 3.

We claim:

The ornamental design for a collapsible three-mirror vanity case, substantially as shown.
